Primary Examiner — Karen S Acker(74) *Attorney, Agent, or Firm* — Wolf, Greenfield & Sacks, P.C.(57) **CLAIM**

The ornamental design for a pad, as shown and described.

DESCRIPTION

FIG. 1 is a bottom, front, side perspective view of a pad showing our new design.

FIG. 2 is a top plan view thereof;

FIG. 3 is a bottom plan view thereof;

FIG. 4 is a front elevational view thereof;

FIG. 5 is a rear elevational view thereof;

FIG. 6 is a right side elevational view thereof; and,

FIG. 7 is a left side elevational view thereof.

The diagonal broken lines within the solid line boundaries shown in FIGS. 1 and 3 represent stitching that is part of the claimed design. The dash-dot-dash broken lines shown in FIG. 2 define boundaries of the pad and form no part thereof. All other broken lines in FIGS. 1-7 represent unclaimed portions of the pad and form no part of the claimed design.
